(57) **CLAIM**

The ornamental design for an art easel, as shown and described.

DESCRIPTION

FIG. 1 is a perspective view of the art easel showing my new design;

FIG. 2 is a front elevation view thereof;

FIG. 3 is a rear elevation view thereof;

FIG. 4 is a side elevation view thereof, the opposite side elevation view being identical to the side shown;

FIG. 5 is a top plan view thereof;

FIG. 6 is a bottom plan view thereof;

FIG. 7 is a perspective view thereof opened; and,

FIG. 8 is a perspective view thereof attached to a tripod. The broken lines showing portions of the art easel in FIGS. 1-3 and 6-8 and a tripod in FIG. 8 are included to show features that form no part of the claimed design.
